UNITED STATES PATENT OFFICE.

MAX GARBELL, OF CHICAGO, ILLINOIS, ASSIGNOR, BY MESNE ASSIGNMENTS, TO O. D. JENNINGS & COMPANY, OF CHICAGO, ILLINOIS, A CORPORATION OF ILLINOIS.

TYPEWRITING MACHINE.

Application filed May 31, 1921. Serial No. 474,029.

To all whom it may concern:

Be it known that I, MAX GARBELL, a citizen of the United States, residing at Chicago, in the county of Cook and State of Illinois, have invented a certain new and useful Improvement in Typewriting Machines, of which the following is a full, clear, concise, and exact description, reference being had to the accompanying drawings, forming a part of this specification.

This invention relates to improvements in typewriting machines.

One object of my invention is to provide a typewriting machine having an improved positively and uniformly-acting back-spacing arrangement operable in any case shift position of the platen.

More specifically, the object of my invention is to provide a back-spacer arrangement of a simple, economical and efficient operation, which is particularly adapted for typewriters having a removable platen and platen frame, and wherein the parts of the back-spacer mechanism are unaffected by the removal or replacement of the platen and frame carrying the same.

More specifically, an object of my invention is to provide a back-spacer arrangement for typewriters, which back-spacer arrangement may be manufactured and assembled as a unit and then applied as a unit to the platen carriage.

Other objects of the invention will more clearly appear from the description and claims hereinafter appearing.

In the drawings forming a part of this specification, Figure 1 is a part elevational view, part vertical sectional view looking at the back of a typewriter, some of the parts being also broken away to more clearly illustrate the details of construction. In this figure, the back-spacer mechanism is shown in its inoperative or normal condition. Fig. 2 is a view similar to Fig. 1 but illustrating the positions assumed by the various parts of the back-spacer mechanism at the end of the depression of the back-spacer key. Fig. 3 is a detail perspective of the back-spacer mechanism unit proper, detached and also illustrating the relative position of the spacer rack carried by the platen carriage. In Fig. 3, the position of the parts of the back-spacer mechanism corresponds to the normal or inoperative condition. Fig. 4 is a view similar to Fig. 3 illus-

trating the position assumed by the parts at the end of the actuating stroke of the back-spacer key. And Fig. 5 is a vertical sectional view taken from the front to the back of the typewriter showing more particularly the back-spacer key and operative connections therefrom to the back-spacer mechanism proper. The full lines illustrate the normal or inoperative position of the parts and the dotted lines the position assumed by the parts at the end of the depression of the back-spacer key.

In the drawings I have only deemed it necessary to illustrate such parts of the typewriter as are directly concerned with the back-spacer mechanism, and sufficient of the arrangement of the removable platen carriage to illustrate my improvements in such type of a typewriter. For a more complete disclosure of the other details of the typewriter and removable platen carriage, reference may be had to my prior Patent No. 1,305,893, granted June 3, 1919, and my pending applications 360,958, filed February 24, 1920, and 464,133, filed April 25, 1921.

In the drawings forming a part of this specification, the main frame of the machine is indicated at 10, the same having a back wall 10^a and mounted upon suitable cushions 11-11. A bridge 12 extends crosswise of the typewriter, said bridge being shown in section in Fig. 5. A back-spacer key 13 is also shown, the same being of the usual or desired form and pivoted on a transversely extending pivot rod 14. A retracting spring 13^a is connected at one end to said lever 13 and at its other end to the bridge 12. Pivoted connected to the inner end of the back-spacer key lever is a lever 15 pivotally mounted on the pivot screw 16, as indicated in Fig. 5. The pivotal connection between the spacer lever 13 and lever 15 may be of any approved form, the same shown comprising an enlarged headed pin 17 on the lever 15, which is adapted to be first inserted through an enlarged opening 18 in the spacer lever 13 and then slipped lengthwise into a communicating slot 19.

At its opposite end, the lever 15 is pivotally connected by an enlarged headed pin 20 with a twisted sheet metal link 21, which in turn is pivotally connected, as indicated at 22 (see Figs. 1 and 2), with a right-angled lever 23. One arm of said lever 23 is pivotally attached to the back wall 10^a.

of the main frame, as indicated at 126, to thereby adapt the lever 25 to oscillate in a vertical plane parallel with the back wall 10^a. The lever 25 has an upwardly extending arm, which is offset inwardly of the machine, as indicated at 26.

The removable platen carriage (and by the terms "platen carriage" I mean to include the platen proper, the frame directly carrying the platen proper and the sub-frame along which the platen frame is longitudinally movable in a well-known manner) is shown as having a platen roller proper 27, a longitudinally extending rail 28, a longitudinally extending spacer rack 29, rigid with respect to the platen frame but adapted for limited vertical adjustment with respect thereto by means of set screws 30 and elongated slots 31, and a paper-feed guide 32. The carriage is made removable with respect to the main frame of the typewriter by suitable means—such as shown in my said application 360,958 and application 464,133. Briefly stated, the sub-frame of the carriage is provided with a pair of laterally-spaced rigid guides suitably apertured to slide vertically up and down a pair of guide posts 33 mounted on the main frame of the machine.

As is customary in typewriters, I provide a spring motor, as indicated conventionally at 34 in Figs. 1 and 2, which is operatively connected with a gear wheel 35, the latter having geared engagement with the spacer rack bar 29, the function of the spring motor being to advance the platen carriage automatically step by step as the printing takes place, the carriage ordinarily being returned the full distance by direct manual shifting, as will be understood. Said spring motor is carried on a relatively heavy pivot screw 36, which, in turn, is supported on a stamped and formed plate 37 rigidly attached to the sub-frame of the carriage.

In the drawings I have also illustrated a desirable form of escapement mechanism, said escapement mechanism comprising a pinion 38 in mesh with the rack bar 29 and a ratchet wheel 39 united to the pinion 38, both being loosely rotatably mounted on the shaft 40. Cooperable with the ratchet wheel 39 is a pawl 41, which is pivotally and slidably mounted by means of the pivot pin 42 and slot 43 on an oscillating plate 44. Said plate 44 is in turn pivotally mounted to swing about a horizontal axis on the bracket plate 37 by means of adjustable pivot screws 45—45. A coiled spring 46 is attached to a depending arm 47 of the pawl 41 and to a shoulder 48 carried by the plate 44. Said plate 44 also carries a tooth rigid or integral therewith (broken away, however, to avoid confusion in the drawings), which tooth will alternate with the pawl 41 in engagement with the ratchet wheel 39 to effect the step

by step escapement or advancement of the platen. Said oscillating plate 44 is formed with a depending arm 49 which is adapted to be actuated by suitable connections from the universal bar of the machine.

The back-spacer mechanism proper, as shown, includes a member designated generally by the reference A; an operating link B; a return spring C; and a second spring D.

The member A is of special stamped and formed construction. Said member A is formed with an elongated normally horizontally extending slot 50 providing a slideable pivotal connection in conjunction with the pivot screw 51 which is carried by the plate bracket 37. Extending in the same general horizontal plane, and on the opposite side of the pivot 51 to the slot 50 is a finger 52, which is inwardly offset from the main plane of the member A, as indicated at 52^a in Figs. 3 and 4. Said finger 52 is rounded, as indicated at 53, to thereby provide a cam adapted to ride upon and along a horizontally extending shelf or ledge 54, which is preferably formed integrally with the bracket plate 37 by suitably stamping the latter, as will be clear from an inspection of Figs. 3 and 4. In normal position of the parts, said cam 53 has its lowermost point somewhat below the upper surface of the shoulder 54 and slightly spaced therefrom to the right, as viewed in Fig. 3.

The member A, directly beneath the pivot pin 51 when the parts are in normal position, has a depending arm 55 which is inwardly offset, as indicated at 56, and then provided with a normally horizontally-positioned extension 57, the free end of which is bent upwardly, as indicated at 58, and then twisted at right angles so as to provide an upper tooth 59 adapted to co-operate with the teeth of the rack bar 29. In normal position of the parts, as shown in Figs. 1 and 3, said tooth 59 is positioned just below the teeth of the rack bar, so as to clear the latter and avoid interference with the normal step-by-step advancement of the platen.

The elongated link B is pivotally connected with the depending arm 55, as indicated at 60, and is also inwardly offset, as indicated at 61, so that the main portion of the link B extends substantially parallel to, and relatively close to, the extension 57 of the member A. Said link B may be upwardly offset as indicated at 62. At its free end, the link B is provided with a headed stud 63 upon which is loosely mounted an anti-friction roller 64, the latter having rolling engagement with the upwardly extending arm 26 of the lever 25, as illustrated in Figs. 1 and 2. The enlarged head of the stud 63 serves to keep the link and arm 26 in operative relation. To confine the link B to a

proper sliding movement, the same may be passed through a suitably apertured guide 65 secured to the rail 28, as illustrated in Figs. 1 and 2.

5 The spring C is connected at one end, as indicated at 66, to the link B, and at its opposite end to a suitable pin 67 carried by the sub-frame of the carriage.

The small coil spring D is interposed between the link B and the member A to the left of the pivots 51 and 60, as shown, and said spring is held in position by seating the ends thereof over suitable studs 68 and 69 formed on the member A and link B, respectively. Said spring D is an expansion spring normally tending to swing the member A in a clockwise direction about the screw pivot 51 when the parts are in normal position, but which, on account of its being 20 of lesser strength than the spring C, produces a different action, as hereinafter explained.

The operation is as follows, assuming that the operation begins when all of the parts 25 are in normal position. As the operator depresses the back-spacer key 13, the lever 25 will be oscillated in a counter-clockwise direction about the pivot 26 from the position shown in Fig. 1 to the position shown in 30 Fig. 2. At this point, it will be noted that this operation obtains regardless of the case shift position of the platen, and, further, that the connection between the link B and the lever 25 is such as to admit of the removal and replacement of the platen carriage without disturbing the back-spacer mechanism and without requiring any attention being paid thereto. As the lever 25 is 35 swung, as above described, the link B is pulled toward the left, as viewed in Figs. 2 and 4. Upon the initiation of the movement of the link B, as above described, and which is against the tension of the spring C, the first effect is for the link B to slightly oscillate the member A in a clockwise direction 40 about the screw pivot 51, and this action is cumulative with the action of the spring D. Said oscillation of the member A elevates the cam 53 and also simultaneously and prior 45 to any sliding movement of the member A, the tooth 59 of the latter is immediately projected into engagement with the corresponding space between two teeth of the rack bar 29. Further oscillation of the member A is then prevented by reason of the engagement of the tooth 59 with the rack bar, and, consequently, the movement of the link B toward the left compels the member A to slide horizontally over the pivot 51, which is permitted by reason of the slot 50. As the sliding movement of the member A begins, the cam 53 rides up onto the fixed shoulder or ledge 54, and then along the same until final position is assumed, as 50 shown in Fig. 4. During this sliding move-

ment, it will be observed that there is no possibility of the tooth 59 becoming disengaged from the rack bar, and, consequently, there can be no slip or skip of the platen in the back-spacing movement. In actual 70 practice, the movement of the link B will be made such that the tooth 59, while engaging with the rack bar 29, will move the latter and platen toward the left or in back-spacing direction a distance equal to 75 two of the teeth of the rack bar 29.

During the back-spacing movement above described, it is evident that the ratchet 39 will be rotated in a counter-clockwise direction equal to two teeth of the ratchet wheel 80 and the tooth 70 thereof will slip over the tooth of the pawl 41 and advance from the position shown in Fig. 1 to the position of the tooth 70 shown in Fig. 2. During this action, it will be observed that the pawl 41 85 has also been permitted a movement toward the right, as viewed in Figs. 1 and 2, from the position shown in Fig. 1 to the position shown in Fig. 2, this movement being commensurate with the length of the slot 43. 90

Upon the operator now removing the pressure from the back-spacer key 13, the latter will be retracted by the spring 13^a and simultaneously the link B will start to move toward the right, as viewed in Figs. 1 to 4 95 of the drawings under the contraction of the spring C. During the initial portion of the return movement of the parts, it will be observed that the tooth 59 of the member A cannot become disengaged from the rack bar 29 because of the fact that the cam 53 is still riding upon the stationary shelf or ledge 54, and the parts are so proportioned that the engagement of the tooth 59 with the rack bar 29 is maintained until the rack bar 29 100 has returned a distance corresponding to the space of one tooth of the rack bar 29. At this point in the action, the pawl 41 will have assumed its operative relation with the ratchet wheel 39 corresponding to the position shown in Fig. 1, except that the pawl 41 will then be in engagement with the tooth 70 representing a counter-clockwise rotation of the ratchet wheel 39 amounting to one 105 space, and, accordingly, a backward movement of the platen equal to one space. As this condition of the parts is reached, the cam 53 of the member A is free to slide off of the stationary shelf 54 and the member A is then depressed so as to disengage the tooth 59 from the rack bar 29. As the member A slides back to its normal position, as shown in Fig. 3, and when it is prevented from further sliding movement with 110 respect to the pivot 51, the spring D, under its expanding action, insures the complete depression of the member A or oscillation in a counter-clockwise direction about the pivot 51, since the force of the expanding spring D depresses the adjacent part of the 115 120 125 130

link B and this in turn forces the oscillation of the member A about the pivot 51.

From the preceding description, it will be observed that the arrangement is such as to positively and instantaneously compel the tooth 59 of the member A to engage the rack bar 29 upon the initiation of the back-spacing operation; that this engagement between the tooth 59 and rack bar 29 is positively maintained during the remainder of the actuating stroke by reason of the cam 53 riding along the stationary shelf 54; that during the return movement of the parts of the back-spacer mechanism, the tooth 59 is prevented from disengagement from the rack bar 29 until the pawl 41 and ratchet wheel 39 have entered into final operative relation and stop further movement of the platen toward the right, as viewed in Figs. 1 and 2; and that, during the final portion of the return movement of the parts, the arrangement compels the proper disengagement of the tooth 59 from the spacer rack bar 29. It will further be observed that the essential parts of the back-spacer mechanism may all be assembled as a unit upon the plate bracket 37 and said unit applied as such to the sub-frame of the platen carriage, thereby minimizing the cost of assembling. The sheet metal portions of the essential parts of the back-spacer mechanism may be manufactured by the ordinary steps of stamping and forming in quantities at small expense, and, on account of the few parts involved, the arrangement is not likely to soon get out of order.

Another important feature of my invention to which I wish to call attention is the following. In present forms of back-spacer mechanisms, it frequently occurs that a fast operator will strike the back-spacer key quickly and with considerable force and immediately release it. This causes the platen to acquire a considerable momentum which carries it in a back-spacing direction more than is intended for the reason that the back-spacing pawl or other element becomes

disengaged upon removal of the pressure from the back-spacer key, and while the platen is still under momentum. With my construction this is impossible for the reason that the tooth 59 cannot be disengaged from the rack 29 so long as the cam 53 is riding upon the shelf 54. In other words it is impossible to overthrow the platen with my construction during a back-spacing movement.

I have herein shown and described what I now consider the preferred manner of carrying out the invention, but the same is merely illustrative and I contemplate all changes and modifications that come within the scope of the claims appended hereto.

I claim:

1. As an article of manufacture, a back-spacer mechanism for typewriters, including: a bracket adapted to be secured to the platen carriage, a back-spacer pawl pivotally and slidably mounted on said bracket, a connecting link pivotally attached to said pawl, and an expansible spring interposed between said pawl and said link at points intermediate the pivotal mounting of the pawl and the pawl tooth proper thereof.

2. As an article of manufacture, a back-spacer mechanism for typewriters, including: a bracket adapted to be secured to the platen carriage, a back-spacer pawl pivotally and slidably mounted on said bracket, a connecting link pivotally attached to said pawl, an expansible spring interposed between said pawl and said link at points intermediate the pivotal mounting of the pawl and the pawl tooth proper thereof, and a shelf integral with said bracket, said pawl having a cam portion adapted to slide upon and along said shelf.

In witness that I claim the foregoing, I have hereunto subscribed my name this 16th day of May, 1921.

MAX GARBELL.
